ELECTRICALLY-ACTUATED SIGNALING
DEVICE

George R. Fish, Norwalk, Conn., assignor to Edwards Company, Inc., Norwalk, Conn., a corporation of New York

Application March 20, 1951, Serial No. 216,561

40 Claims. (Cl. 340—401)

1

This invention relates to electrically actuated mechanisms, particularly electric signalling devices such as an electric bell.

One of the objects of this invention is to provide a practical and efficient electric signalling device which is constructed to provide dependable safeguards against foreign matter, such as water, moisture, dust, and the like, or against the hazards of explosive atmospheres, and thereby achieve reliable maintenance and safety of 10 operation of the device. Another object is to provide a device of the above-mentioned character which is simple and practical in construction and assembly, may be installed with facility, and well adapted for long continued use or operation under adverse conditions such as those just mentioned above. Another object is to provide a signalling device that is well adapted to withstand the varying conditions of use and operation on shipboard, such as humidity, water, including submersion, and wide changes in temperature, including freezing temperatures, and the like.

Another object is to provide an electric gong signalling device in which the electric actuating parts are dependably protected and sealed, for example, against the elements of weather or the like, and yet the gong striker maintained unimpaired in achieving the desired audible signalling. Another object is to provide a gong and striker mechanism that is capable of dependable operation under conditions of moisture, wetness, rain, and even freezing; another object is to carry out this last-mentioned object by a construction that is well adapted for fabrication, assembly, and installation. Another object is to provide an electric bell or like signalling device that can be safely operated throughout a wide range of varying conditions of practical use and maintain reliability or dependability of actuation.

Another object is, in general, to provide an improved device of the above-mentioned character. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings, in which similar characters refer to similar parts throughout the several views,

Figure 1 is a front elevation of the signalling 55 device as installed in use;

2

Figure 2 is a side elevation as seen from the right in Figure 1, certain parts being broken away to show certain other parts more clearly;

Figure 3 is an exploded view as seen from the right in Figure 1 or from the front in Figure 2, showing also the internal striker actuating mechanism in one form or embodiment thereof;

Figure 4 is an elevation as seen along the line 4—4 of Figure 3;

Figure 5 is a vertical sectional view as seen along the line 5—5 of Figure 3;

Figure 6 is a fragmentary sectional view as seen along the line A—A of Figure 1, showing the relationship between gong, striker, and one form of striker actuating mechanism;

Figure 7 is a detached elevation of a sub-assembly as seen along the line 7—7 of Figure 6;

Figure 8 is a detached elevation of a modification of the sub-assembly of Figure 7, as seen along the line 7—7 of Figure 6;

Figure 9 is an electrical diagram showing the connections in the embodiment of Figure 8;

Figure 10 is a fragmentary sectional view like that of Figure 6 showing the striker actuating mechanism arranged for ice-breaking and the relationship therebetween and the gong and striker;

Figure 11 is a fragmentary sectional view as seen along the line A—A of Figure 1, showing another form of construction for achieving certain other advantages and constructed for optional employment of the feature of ice-breaking;

Figure 11^a is a detached fragmentary portion of the view of Figure 11, on an enlarged scale, to show certain features more clearly;

Figure 12 is a detached elevation of the sub-assembly employed in Figure 11, being a fragmentary elevation as seen along the line 12—12 of Figure 11;

Figure 13 is an electrical diagram showing a possible form of circuit connections in the form of Figures 11 and 12;

Figure 14 is a detached elevation of a modified form of sub-assembly as seen along the line 12—12 of Figure 11;

Figure 15 is a fragmentary sectional view as seen along the line A—A of Figure 1, showing a modified form of construction adapted to achieve other advantages;

Figure 16 is a detached elevation of the sub-assembly employed in the form of Figure 15 and illustratively embodying an interrupter;

Figure 17 is a view like that of Figure 15 show-

ing the mechanism arranged for ice-breaking; and

Figure 18 is a diagram of the circuit connections employed where the device of Figures 15-17 employs an interrupter.

Referring to Figures 1, 2, and 3, I provide a casing which preferably comprises two separable parts which, when assembled, form a sealed or airtight enclosure; in the preferred form illustrated, this casing comprises companion parts 20 and 21, of which the part 20 may be constructed in the form of a box and the part 21 in the form of a closure or cover plate therefor. The part 20 may have a bottom wall 22 and side walls 23 and they are provided with a suitable knock-out, one of which is shown in Figure 2 at 24, whereby to provide a hole or opening through which a conductor-carrying conduit (not shown) may be mechanically secured and placed in sealed connection therewith in any suitable or known manner, thus to extend the electric circuit to the interior of the casing. The latter may be mounted in desired position in any suitable manner and, for example, if it is to be surface-mounted, the box-like casing part 20 may be provided with apertured ears or lugs 25 by which they may be bolted or otherwise secured to a wall or other support.

The conductors (not shown), usually two in number, thus brought into the casing are connected to binding screws 26 (Figures 5 and 3) of the socket part 27 of a separable two-conductor plug and socket connecting device, the plug part 28 (Figures 4 and 3) of which is carried by the companion casing part 21 in a manner later described. These separable connector parts may be of any suitable construction. The socket connector part 27, comprising a suitable body of insulating material, is secured, as by screws (not shown), to a bracket plate 30 stepped, as shown in Figures 2 and 3, to have a portion overlying a heavy boss 31 cast integrally with the casing wall 22 to provide good support for screws 32 by which the bracket 30 is secured to the boss 31. The boss 31 makes it unnecessary to drill the screw holes through the back wall 22.

As shown in Figure 5, the socket-connected part 27 has two spaced rectangular sockets or recesses 27^a into which the two contact prongs 28^a of the plug part 28 enter for making internal connection with the circuit of the conductors connected to the binding screws 26. The plug connector part 28 is rigidly mounted on the inside face of the cover plate 21 by means of a U-shaped bracket 33 to the cross-part of which the insulating body of the plug part 28 is secured, as by screws 35 (Figure 4), the two arms of which U-shaped bracket being secured to the cover plate 21 in any suitable manner, as by stepping them (see Figure 3) at their free ends for reception in suitable spaced holes 34 (see Figures 1 and 3), whereupon the reduced ends are peened or headed over. The resultant cold-flow of metal not only securely anchors each bracket arm to the front plate 21, but also expands the metal into the respective plate holes and achieves a good sealed joint, particularly where the metal of the parts is the same and of a composition like brass. The plug part 28 is provided with suitable means, such as conductive tabs or ears 28^b (Figures 3 and 4), for securing the ends of conductors of the electric actuating mechanism, the connectors 28^b being internally in connection with the respective prong parts 28^a.

The separable plug and socket connector thus coacts to insure that the companion casing part

must always be assembled to the mounted or secured casing part in the same way, and thus they coact to orient the companion casing parts upon assembly thereof. The companion casing part 20 comprises also a re-entrant casing part in the form of a metal tube 36, of brass, for example, that is closed or sealed off at its inner end, as at 36^a (see also Figure 6), and it is integrally secured to the front plate 21 so that it extends upwardly and inwardly into the box-like casing part 20 at an inclination to the front plate 21 such that it makes an angle to the plane of the plate 21 substantially as shown in Figure 3 and makes an angle to the vertical axis X—X as seen in Figures 1 and 4, substantially as is better shown in Figure 4, intersecting the plate 21, preferably at a point laterally displaced from the axis X—X (to the right in Figure 4 and to the left in Figure 1). As is better shown in Figure 3, the re-entrant casing part or tube 36 projects somewhat through and beyond the external face of the plate 21, the latter being provided with a suitable elliptical or oval hole (Figure 6) into which the metal tube 36 fits and to the walls of which it is secured, as by brazing, as indicated at 37 in Figure 6. The part 36 is thus securely held at the above-described angularities to the axis X—X, the angles being substantially on the order of magnitude as indicated in the drawings, and the brazed or soldered junction 37 makes a sealed joint.

The casing part 20 (Figures 1 and 3) may be provided with a peripheral flange 38 which underlies the marginal portions of the front plate 21; in this marginal portion of plate 21 and in the casing flange 38 are provided suitable means that can coact with the plug and socket connector 27—28 to prevent assembly of the companion casing part 21—36 to the casing part 20 excepting with the axis X—X always vertical and with the re-entrant casing part 36 therefor always projecting upwardly and inwardly into the box-like casing part 20 and thereby also maintain the angularity shown in Figure 4; this means may comprise holes 38^a and 38^b, conveniently on a diameter, in the flange 38 and studs 40 in the marginal portion of the front plate 21 for entry into the holes 38^a and 38^b. The socket connector part 27 (Figure 5) is positioned transversely of and near the lower end of this vertical axis, and so is the plug connector part 28, the contact prongs of the latter entering the socket contacts of the former as the studs 40 enter the holes 38^a and 38^b.

The two casing parts are preferably detachably secured together and their junction sealed, as by screws 41 that pass through suitable holes in the marginal part of the closure plate 21, being threaded into suitable bosses 38^c formed in the casing flange 38. Projecting forwardly from the flange 38 is a circular gasket-locating flange 42 (Figures 1 and 3) which may be of the same diameter as that of the wall 23 of casing part 20 and of which it forms a part where, as is preferred, the flange 38 is separately constructed as a ring or collar and secured to the casing wall 23, as by brazing or the like, indicated at 43 in Figure 3; a rubber ring gasket 44 is seated in the external angle between the flanges 42 and 38, and when the screws 41 are tightened up, the gasket is compressed and forms a continuous seal between the plate 21 and the casing wall 23 (Figure 2), portions of the bosses 38^c limiting the extent to which the screws 41 can draw the parts 21 and 20 together and acting to maintain them parallel.

assuring uniform compression of the gasket 44 throughout.

Externally of the resultant sealed enclosure and in appropriate relation to the open end 36^b of the re-entrant casing part 36, I mount a signalling means that is to be actuated by the electro-responsive means (later described) that is housed within the enclosure; in the illustrative embodiment, this signalling means comprises a gong 45 positioned to overlie the projecting part of the part 36 (Figures 1, 2, and 6), being securely fastened to a large stud or post 46 secured to the plate 21 and positioned on the axis X—X (Figure 1). Post 46, preferably circular, is provided with an end face 46^a which is conformed as nearly as possible to the inside face of the central portion of the gong 45 to provide a substantial supporting area therefor; a screw 47, provided with a lock washer, passes through a central hole 45^a in the gong and is threaded into a threaded hole in the post 46 to clamp the gong 45 in position, and preferably there is interposed between these two parts a disc-like washer of a relatively hard but somewhat yieldable material, preferably non-metallic, such as hard fiber or hard rubber, and yet capable of yielding somewhat under the clamping pressure to conform itself to slight irregularities in the adjacent gong and post surfaces and thereby insure substantially uniform clamping pressure throughout.

Before assembling the gong to the post 46, there is inserted into the re-entrant casing part 36 a gong striker in the form of a rod 50 and an actuator therefor in the form of a paramagnetic plunger 51, preferably with a spring 52 interposed between the sealed end 36^a and the inner end of the plunger 51, as is indicated in Figure 6. The spring is preferably made of a material like Phosphor bronze. The plunger 51 and the striker 50 are made corrosion-resistant in any suitable way; for example, the plunger 51 may be of soft iron, chrome-plated, and the striker rod 50 may be of stainless steel. The spring 52 is well protected, being completely enclosed between the inner end of plunger 51 and the sealed end 36^a of the tubular casing part 36 whose interior surface serves as a guidway for reciprocating movement of the plunger 51, the relative diameters providing ample clearance, on the order of several thousandths of an inch, for adequate freedom of reciprocating movement throughout the conditions of practical use. Some compression or expansion of air between the inner end of plunger 51 and the sealed tube end 36^a may take place during the strokes of reciprocation of the plunger, the air in that inner end space functioning somewhat like a spring, being desirably relieved to the desired extent by leakage in the clearance between the plunger and its guiding tube wall. Where, as is preferred, spring 52 is employed, the just-described action can serve to supplement the action of the spring itself.

In normal or at-rest position, the parts 50 and 51, tending by their weight to slide downwardly (Figure 6), are preferably given a position wherein the striker 50 is out of contact with the gong 45; this is of advantage in that water, as from condensation or rain or the like, that might run down along the inside surfaces of the gong 45, as viewed in Figures 1 and 2, is prevented from accumulating as it would at the point or area of engagement between the striker and the gong surfaces; such water runs to and tends to accumulate as it spills off on the inside face of the peripheral or skirt portion 45^a (Figure 6) at the

six o'clock position as seen in Figures 1 and 2, where in sufficiently low temperatures it might freeze and build up as it freezes. But the lower open end of the tubular casing part 36, while terminating close to the inside surface of the skirt-like gong portion 45^a, is juxtaposed to that portion of the gong at a point angularly displaced from this six o'clock position, illustratively at about the 7 o'clock position as shown in Figure 1, so that the striker 50 can impact against the gong 45 in a region free from accumulated water or ice, the withdrawn at-rest position of striker 50 coacting toward achieving these advantages. Moreover, under such illustrative adverse weather conditions, the plunger and striker remain well protected as no water or the like can enter and remain in the tubular casing part 36, the externally projecting portion of the latter giving good protection, particularly against water running down the outside face of the cover plate 21. Even if the structure as viewed in Figures 1, 2, and 6 were to be submerged or a water level rise above the lower end of re-entrant casing part 36, the plunger 51 and the surfaces of part 36 along which it reciprocates, as well as the spring 52, remain dependably protected because the trapped air in the re-entrant casing part 36 prevents rise of water into the part 36; not only is dependable reciprocating action of the plunger 51 maintained under such conditions, but when those conditions are removed, the actuating parts remain unimpaired. The part 36 is also preferably corrosion-resistant, and while for some purposes it may be made of brass or the like, it is preferably chrome-plated or it may be made of stainless steel.

Within the sealed casing 20—21—36 and assembled to the inwardly projecting portion of the tubular casing part 36 is a winding 55 (Figures 3, 4, and 6) for producing a magnetic field and to coat in the actuation of the external paramagnetic plunger 51, receiving its energy by suitable conductors connected to the connector tabs 23^b of the plug connector 23 (Figure 4). Winding 55 is preferably wound in the form of a solenoid winding, for which the plunger 51 is the movable core, and preferably it is constructed as part of a sub-assembly unit. The winding 55 is wound upon a form or spool which may comprise a sleeve 56 and end plates 57 and 58 of suitable insulating material, such as hard fiber, having an internal diameter so that it may be easily slid onto the tubular casing part 36. It is preferably secured to a flat supporting plate 60 (Figures 3, 4, 6, and 7), shaped substantially as shown in elevation in Figure 7, having a relatively large cut-out or opening 60 into which a portion of the winding unit projects; one of the insulating end plates 58 is extended, as at 58^a (Figures 3 and 6) to project materially to the other side of the supporting plate 60, and in the extension 58^a are secured, as by eyelets, connector tabs 61 and 62 to which the ends of the winding 55 are permanently connected and to which the conductors that lead to the connector plug 23 may be connected, as by soldering, as indicated in Figure 3.

On the inside face of cover plate 21 are secured two spaced brackets 63 and 64; these may be of heavy brass sheet material, and each is substantially a right-angled triangle in shape with the hypotenuse resting against the cover plate 21 (Figure 3). These brackets are secured to the plate 21 in any suitable manner, as by integral ears or lugs formed thereon and that extend into suitable spaced holes in the plate 21 where they

are peened or riveted over, as at 63^b and 64^b (Figure 1), to form sealed joints. Brackets 63 and 64 are proportioned so that the flanges 63^a and 64^a thereof fall in a plane that is parallel to the axis of the tubular casing part 36. It is onto these parallel flanges 63^a and 64^a that the plate support 60 (Figure 7) slides as the sub-assembly of winding and plate support is assembled to the tubular casing part 36 by entering the inner end of the latter into the cylindrical bore of the winding sub-unit or spool. The plate support 60 is provided with slots 65, 66 (Figures 4 and 7) which are parallel to each other and parallel to the axis of the bore of the solenoid winding, and through the slots extend screws 67 and 68 (Figure 4) whereby the sub-unit may be adjusted lengthwise of the tubular part 36 and set and secured in a position to achieve the best coaction with the plunger 51; this adjustment and setting is done empirically during assembly and testing.

Since gongs like the gong 45 are usually shaped out of suitably heavy sheet metal, there might be non-uniformity in thickness or the hole 45^a (Figure 3) might be a bit off center. Such factors as these might upset the effect of the above-described internal setting of the winding and related parts were the gong to partake of rotary displacement or were it to be removed and then put back in some other rotary position. Accordingly, at a suitable point offset from the center, I provide in the gong supporting post 46 a pin 76 (Figures 1 and 3) that projects beyond the end of the post, and in the gong 45 I provide a hole 71 into which the pin is received and fits upon securing the gong to the post. The pin 76 thus coacts to prevent rotary displacement of the gong and also, where one is employed, of the semi-hard interposed pressure distributing member 48 (Figure 3).

The winding 55, in so far as certain features of my invention are concerned, may be energized in any suitable manner to achieve the desired actuation of the plunger 51 and striker 50 for either single or repeated striking of the gong 45. If a circuit interrupter is employed, as is usually the case for direct current operation, the interrupter is also contained within the sealed housing and any sparking is rendered harmless, permitting the structure to be used with safety in explosive atmospheres. Sometimes, for alternating current operation, a rectifier is employed to utilize the pulses of half-waves, and in such case the rectifier is also housed in the sealed casing and similar safety of operation achieved. Such additional devices I preferably assemble to form part of the sub-unit that comprises the winding 55 and plate support 60, connecting the devices in circuit with the winding on the sub-unit and leaving the terminal connector conductors, leading from the insulating extension 58^a (Figure 3), for connection to the plug connector 28. For alternating current operation, particularly where the plunger and striker are to reciprocate synchronously, a circuit interrupter need not be employed.

In the preferred forms of my invention I employ a permanent magnet to coact with the plunger 51 to hold the striker 50 in the above-described at-rest position wherein it is out of contact with the gong 45, and this permanent magnet may or may not, as desired, coact with the magnetic flux of the winding 55 in reciprocating the plunger 51. An arrangement in which it does so coact will first be described, an arrangement in which the winding 55 is energized by alternating current to produce an alternating

magnetic flux, with which the unidirectional flux of the permanent magnet coacts to achieve synchronous reciprocation of the plunger and striker.

In this form, and referring first to Figure 7, I provide a permanent magnet 72 in the form of a rectangular bar or block of highly retentive magnetized material, such as Alnico, capable of producing a magnetic flux that is relatively large in relation to that produced by the winding 55; for example, where the solenoid winding when energized by alternating current produces a peak magnetizing effect of about 850 ampere turns, equivalent to about an average or mean value of 600 ampere turns, the permanent magnet may have a magnetizing effect on the order of 1,400 ampere turns. The latter may be physically inter-related with the plunger 51 and winding 55 in any suitable manner so that the two fluxes can suitably interact, being additive on one half-cycle of energization of the winding 55 and subtractive on the other half-cycle. Preferably I position the permanent magnet 72 off to one side of the winding 55 and extend it by pole piece elements 73 and 74 to bring its unidirectional flux to coact as just described. Pole pieces or pole extension 73, 74 are conveniently in the form of plate-like parts of paramagnetic material, such as suitably heavy sheet steel, which may be given the desired shape and configuration, as by punch-press operations.

As is better shown in Figure 7, the permanent magnet 72 rests against the plate support 60, which is preferably of brass, off to one side of the large substantially rectangular hole 60^a in the plate 60, and it is received between two upstanding lugs or ears 60^b and 60^c formed integrally with the plate support 60. In a direction lengthwise of the axis of the winding 55, the magnet 7 is of the same length as the winding unit 58—55—51, so that these two parts are snugly received between the pole piece plates 73, 74, with the latter parallel to each other and at right angles to the axis of the bore of the winding unit; registering with this bore and of the same diameter are holes 73^a and 74^a in the extension poles 73 and 74, respectively. These have lugs or ears 73^b and 74^b, respectively, that rest against the plate support 60 to which they are secured by screws 75, the end plates 73, 74 bridging across the opening 60^a in the plate 60 and overlying the longitudinal edges of the opening, thereby holding the winding unit in its above-described position in which it projects downwardly through the opening. These end plates also have lugs 73^c and 74^c which overlie the permanent magnet 72 (Figures 6 and 7), and the latter is thus securely held in place.

The relationship of the permanent magnet extension poles 73, 74 to the tubular casing part 36 and the plunger 51 in the latter is substantially as is better shown in Figure 6, wherein flux from the unidirectional field of the permanent magnet 72 flows in a magnetic circuit which includes the permanent magnet 72 and pole piece 74, thence in a general radial direction from the annular surfaces about the hole 14^a to the plunger 51, thereby crossing a relatively small radial flux gap represented principally by the material of tubular casing part 36, then from the inner or upper end of plunger 51 in a general axial direction along a correspondingly axial flux gap to the annular surfaces at the hole 73^a, and then along the pole extension 73 and back to the permanent magnet 72; the resultant pull exerted 70 on the plunger 51 is resisted by the spring 52

which, as a result, may be compressed and the resultant balance of pull and spring forces holds the plunger 51 in about the position shown in Figure 6 and the striker 50 out of engagement with the gong 45. By means of the slots 56-58 and the screws 67-68 (Figures 4, 6, and 7), the entire sub-assembly (of Figure 7) may be adjustably positioned along the length of the tubular part 36, the latter extending through the bore of the sub-assembly, and that includes the holes 73^a and 74^a of the pole piece extensions.

When the winding 55 is energized with alternating current, the flux produced thereby is in effect superimposed upon the unidirectional flux of the permanent magnet, in the above-described magnetic circuit. On one half-cycle the winding flux is in the same direction as the permanent magnet flux, and the plunger 51 is forcibly drawn upwardly, further compressing the spring and tending to shorten the above-mentioned axial flux gap between the plunger and the pole piece 73; on the succeeding half-cycle the winding flux is in opposite direction, the magnetic pull on the plunger 51 is greatly reduced, and the energy stored in spring 52 is thus released to snap the plunger 51 downwardly and cause striking of the gong 45, and upon the succeeding half-cycle, with the fluxes now additive, forcibly pull the plunger 51 upwardly to again compress the spring 52, these steps repeating themselves for so long as the circuit of winding 55 remains closed. The above-described adjustability of the sub-assembly along casing tube 36 may be utilized to achieve that setting which gives best ringing action, it being noted that the sub-assembly, when secured in position by the screws 67, 68, forms in effect a steady support for the inwardly projecting tubular casing part 36.

The arrangement just described utilizes both half-waves of the energizing alternating current. Good effects can be achieved, however, by unidirectionally energizing the winding 55, as with a succession of unidirectional pulses. For example, a single-wave rectifier might be included in the circuit of winding 55 so that the latter is energized only by half-waves of one sign of the energizing alternating current; in such case the rectifier, which may be of any convenient form, such as a so-called copper-oxide-iron rectifier, may be included in the above-described sub-assembly, as is shown in Figure 8, wherein such a rectifier, generally indicated by the reference character 77, is shown insulatingly carried by a bracket 78 secured to the plate support 60 on one side of the winding unit, and in Figure 9 is diagrammatically shown how the winding 55 and rectifier 77 of such a sub-assembly are connected in series across the connecting tabs 61, 62 of the insulating plate extension 58^a and from which conductors lead to the connecting plug 28. Where the power stroke of the plunger 51 is in response to energy released by the spring 52, as in the arrangement of Figure 6, the circuit connections are so made that the half-waves or pulses utilized to energize the winding 55 pass through the latter in a direction such that the corresponding flux produced in the above magnetic circuit is in the same direction as that of the permanent magnet.

The arrangement of Figure 6 is of advantage where it is desired to use a relatively long coil spring 52, particularly one that has a non-linear force-deflection characteristic, as by giving it a tapered shape from one end to the other, in order to substantially compensate for the non-linear

relationship between the magnetic force exerted on the plunger and the displacement of the plunger as the axial flux gap changes, an arrangement that coacts in achieving synchronous plunger actuation. The above-described angular position of the re-entrant tubular casing part 36 in relation to the interior of the sealed enclosure permits a substantial length of tubular part 36 to be nicely accommodated.

Under extremely adverse weather conditions it might be possible, in spite of the protective features above described, for the lower end of the striker 50 to become frozen against movement by ice or snow that might somehow accumulate or be formed, for example, in the angle between the plane of the open end of the tubular casing part 36 and the adjacent inside face of the portion 45^a (Figure 6) of the gong 45, and to combat such a condition I may re-arrange the structure of Figure 6 in the manner indicated in Figure 10. The paramagnetic plunger means within the reentrant casing part 36 may comprise a multi-part plunger structure with the parts coacting with each other and with the permanent magnet field and the field of the winding so as to partake of substantially conjoint motion or reciprocation as a unit under certain conditions and to partake of substantial relative axial movement when the striker 50 is immobilized, as by an ice formation. Illustratively, for one part, I may use the plunger 51, as in Figure 6, with which the striker is mechanically connected, and for the other part a somewhat shorter plunger 51^b above the plunger 51 and axially spaced from the latter by a coiled spring 52^a preferably of non-magnetic material, such as brass or Phosphor bronze, and inside of which there extends downwardly a stem 51^c, preferably of non-magnetic material, secured at its upper end to the upper plunger 51^b. Plunger 51^b may be of chromium-plated soft iron. Between the upper end of the latter and the sealed inner end of tubular casing 36 is interposed a coiled spring 52^b which, according to circumstances, may have a non-linear characteristic, if desired.

The several parts are so proportioned that, with the plunger 51 held retracted by the force of the permanent magnet flux, thus holding the striker 50 out of direct contact with gong 45, spring 52^a—which, like spring 52^b, may be under some strain in this at-rest position—holds the upper plunger 51^b more or less out of the axial flux gap between the upper end of plunger 51 and the annular surfaces about the hole 73^a in the extension pole 73, and in that position the lower end of the short stem 51^c is spaced axially away from plunger 51.

When the winding 55 is energized, as herein described, so that its flux is added to that of the permanent magnet along the above-mentioned axial flux gap, the plungers 51 and 51^b move upwardly under the pull exerted on the plunger 51, compressing both springs 52^a and 52^b, and during this action, if the stem 51^c is engaged by the lower plunger 51^b, the latter can thereby directly increase the compression of the upper spring 52^b and the energy stored therein. When the winding flux changes, as above described, to effect a downward stroke of movement of the striker 50, the plunger system is snapped or projected downwardly at substantial velocity as the energy in the two springs is thus released, and during this action some relative axial movement between the plunger parts 51 and 51^b may take place under the action of spring 52^a. The pull

of the permanent magnet flux, upon conclusion of the downward stroke, restores the parts to the at-rest position above described.

However, should the striker 50 be frozen or otherwise immobilized, axial movement of plunger 51, under the control of the winding flux, does not take place and the inner end face of plunger 51 now becomes a flux-guiding face for flux of both permanent magnet and of the winding in an axial flux gap reaching toward the lower end face of plunger 51^b and to the annular surfaces about the hole 73^a in pole piece 73, exerting a powerful pull on the plunger 51^b to snap it downwardly toward the plunger 51, aided somewhat by the spring 52^b, the pull increasing very rapidly as this flux gap shortens; as a result, spring 52^a yields and the stem 51^c is powerfully impacted against the plunger 51, the force of the impact being transmitted to the end of striker 50 to fracture any ice formation at that end. Rounding over or tapering the end of striker 50 is of aid as it acts like a wedge driven into the ice formation. When the energization of winding 55 is such as to diminish the magnetic flux in the now shortened air gap between the two plunger parts, the energy stored in spring 52^a forces the plunger 51^b upwardly toward its at-rest position, as suggested in Figure 10, thus completing one cycle of an ice-breaking stroke with the resultant retractile stroke for the plunger 51^b relative to the striker 50.

It will now be clear that these cycles are repeated at great rapidity, particularly if the winding is energized with alternating current at suitable frequency, usually 60 cycles, the actuation of the ice-breaker plunger 51^b being substantially synchronous therewith. Fragmentation and clearing of the ice formation results in freeing the striker 50 for movement, whereupon continued energization of the winding 55 achieves reciprocation of the system and striker 50 for sounding the gong, in the manner first above described.

The spring and plunger in Figures 6 and 10 are well protected against foreign matter and the effects of weather and the like; nevertheless, it might be desired under some circumstances to eliminate use of a spring. With the gong 45 outside of the sealed casing and desirably detachably secured thereto as above described, when in position it serves to prevent removal of the plunger-striker unit and of the spring, these in effect being external of the sealed enclosure. In Figures 11 and 12 I have shown a form of my invention which has the advantages of assembly and operation without such a spring.

I again employ a sub-assembly that is sleeved onto the inner closed end of the casing tube 36, as before, and it again comprises a plate support 60 having a bar or block type of permanent magnet 72 at one end, held in place by lugs 60^b and 60^c upstanding from the plate 60 and by overlying lugs 73^a and 74^a of the plate-like pole extensions 73 and 74 which are secured by lugs and screws to the support 60 as before. Preferably the permanent magnet 72 is somewhat longer and the spacing between the plate pole extensions 73 and 74 correspondingly larger in order to accommodate therebetween two windings 55^a and 55^b with a paramagnetic plate-like intermediate pole extension 83 (Figures 11 and 12); the intermediate pole piece 83 bridges across the plate opening 60^a and its right-hand edge, as seen in Figure 12, abuts flatwise against the adjacent face of the permanent magnet 72 so as

to be in good flux-conductive contact therewith. Intermediate pole piece 83 has a round hole 83^a therein, and the winding unit and sub-assembly can thus be sleeved onto the inner closed end of the casing tube 36 as shown in Figure 11 and adjustably secured by the screw and slot connection to the internal brackets 63 and 64. It is fixed in a position such that the flux from the permanent magnet 72 holds the plunger 51 (Figure 11) in the desired position with the striker 50 appropriately spaced from the gong 45.

Plunger 51 is of a length shorter than the spacing between the endmost pole extensions 73 and 74, thus providing, when in mid-position, generally axial flux gaps between its ends and the respectively adjacent but spaced pole pieces 73 and 74, with about the central portion of plunger 51 surrounded by the intermediate pole pieces 83, being spaced therefrom by an annular radial flux gap of relatively small dimension, on the order of the thickness of the wall of the casing tube 36. Along these axial flux gaps, flux from the permanent magnet 72 can exert forces on the plunger 51 and these, when affected by the energization of the windings 55^a and 55^b, illustratively in a manner later described, can effect synchronous reciprocation of the plunger and striker and correspondingly impact the gong synchronously.

To hold the striker 50 in an at-rest position out of engagement with the gong 45 against the effect of the weight on plunger and striker tending to slide them downwardly in Figure 11, I may utilize a relationship of parts as is there indicated; this includes giving the striker rod 50 such a length that when its end engages the gong 45, the plunger 51 is in a position where the axial flux gap between its upper end and pole piece 73 is shorter than the axial flux gap between its lower end and the pole piece 74. Accordingly, permanent magnet flux in the magnetic circuit comprising the permanent magnet 72, pole piece 73, upper axial flux gap, plunger 51, intermediate pole 83, and back to the permanent magnet 72, is greater than the permanent magnetic flux in the magnetic circuit comprising permanent magnet 72, intermediate pole piece 83, plunger 51, lower axial flux gap, pole piece 74, and back to the permanent magnet 72, and accordingly the pull on the plunger 51 is greater in an upward direction and plunger and striker rod are moved into and held in an at-rest position somewhat as shown in Figure 11, in which the plunger 51 has its axial mid-point substantially coincident with the central plane between the parallel pole pieces 73 and 83. Actually the plunger 51 is displaced a little bit downwardly from that point of coincidence because of the weight of the movable parts and because of the effect of axial pull downwardly by flux along the lower axial flux gap between the lower end of plunger 51 and the lower pole piece 74. This latter pull is materially diminished because that axial flux gap is of materially greater length. This at-rest position is dependably maintained and in this arrangement the striker rod 50 cannot be held constantly in contact with the gong 45 because that contact prevents the lower axial flux gap from ever becoming shorter than the upper axial flux gap, as earlier explained.

Windings 55^a and 55^b are connected in series, as shown in Figure 13, across the connecting tabs 61 and 62 carried by the insulating plate 58, the serial connection being such that the wind-

ings produce magneto-motive forces and resultant axial flux in opposite directions. When energized by alternating current, on one half-wave winding 55^a produces magnetic flux in the upper magnetic circuit, as viewed in Figure 11, in a direction opposed to the permanent magnet flux in that circuit and winding 55^b produces magnetic flux in the lower magnetic circuit in the same direction as that produced therein by the permanent magnet; accordingly the flux in the lower axial flux gap is greatly increased (in the magnetic circuit comprising the lower part of permanent magnet 72, intermediate pole piece 33, lower part of plunger 51, axial flux gap, lower pole piece 74, and back to the permanent magnet 72), with the result that the plunger and striker are snapped downwardly with substantial velocity and energy. In this manner the plunger and striker are moved out of their at-rest position and at about the moment of impact the lower axial flux gap is exceedingly small, whereas the upper axial flux gap is now of substantial length. On the next and reversed half-wave, the flux of upper winding 55^a is in the same direction across the upper flux gap as is the permanent magnet flux, in the upper magnetic circuit, and the flux from the lower winding 55^b is in a direction opposing the permanent magnet flux across the lower axial flux gap, in the lower magnetic circuit, whereupon the plunger and striker are snapped upwardly, whereupon the succeeding half-wave effects a downward stroke of movement, these actions and steps following in synchronous succession for so long as the circuit of the two windings is maintained closed.

When the circuit is open and the two windings deenergized, the plunger and striker are pulled and held into the at-rest position indicated in Figure 11 and as above described.

The adjustable setting of the winding and permanent magnet sub-assembly (as seen in Figure 12) lengthwise of the re-entrant casing tube 36 along the supporting brackets 63 and 64 is of advantage not only in assembly of the structure in course of manufacture, but also in empirically or during testing speedily achieving the coacting relationships above described.

If desired, instead of using a single elongated bar type of magnet 72 as in Figure 12, two smaller or shorter permanent magnet blocks may be employed as shown at 72^a and 72^b in Figure 14, and in such case the intermediate pole piece can be extended to reach inbetween the two magnets 72^a and 72^b. If the latter are arranged so that the north pole of magnet 72^a engages pole piece 73 and the south pole of magnet 72^b engages pole piece 74, the windings 55^a and 55^b are again connected to produce flux in opposite directions. On the other hand, if one of the magnets 72^a or 72^b is reversed end for end, so as to reverse the direction of flow of permanent magnet flux in its magnetic circuit, the windings 55^a and 55^b are connected to produce fluxes in the same direction. In either case the operation will now be clear in view of the description of the embodiment of Figures 11 and 12.

In these forms the flux-responsive structure for actuating the striker 50 may also be arranged to achieve ice-breaking action to free the striker 50 in case it becomes immobilized by freezing, and this may be done by providing a coacting paramagnetic plunger 51^c, as indicated in Figure 11 and shown on a larger scale in Figure 11a; in this form the plunger 51^c, which may be of soft iron chromium-plated, has a central or axial

bore therethrough so that it may be sleeved onto the striker rod 50 for ease of axial movement relative thereto, striker rod 50 being preferably made of any suitable non-magnetic material. 5 Extending about the striker rod 50 and between the lower end of plunger 51 and the upper end of plunger 51^c is a coiled spring 52^c of such a strength and so dimensioned that, with the moving parts held in the at-rest position above described, the upper end of plunger 51^c just about enters the opening 74^a in the extension pole piece 74, a collar 86 secured to the striker rod 50 limiting downward movement of plunger 51^c along the rod 50, as is better shown in Figure 11a. 10 When the windings 55^a and 55^b are energized as above described, the plunger 51 and striker 50 reciprocate as before, carrying plunger 51^c along with it, and during the strokes of reciprocation little, if any, material relative axial movement 15 between the plunger 51^c and plunger 51 need take place, plunger 51^c barely, if at all materially, entering the axial flux gap between the pole pieces 74 and 83. 20 However, if striker rod 50 is immobilized, thus 25 holding plunger 51 against movement out of its at-rest position, energization of winding 55^b, in a direction to add to the permanent magnet flux in the axial flux gap that extends downwardly from the lower end of plunger 51 to the upper 30 end face of plunger 51^c, exerts a powerful upward pull on plunger 51^c, a pull which increases rapidly as the axial gap is shortened by upward movement of the plunger 51^c, thus compressing spring 52^c and storing substantial energy in it; 35 when the energization of the winding then changes to diminish the flux in the shortened axial flux gap, the energy stored in spring 52^c is released and the plunger 51^c is snapped downwardly at substantial velocity, its kinetic energy, 40 when its downward movement is suddenly halted by the collar 86, being transmitted to the striker rod 50 to fragment or crush the ice accumulation or other cause that immobilizes the striker 50. Under the control of the winding flux, such reciprocation relative to the striker rod 50 and plunger 51 can be repeated in rapid succession, 45 synchronously where the energization is by periodic or successive current pulses, and once striker 50 is freed, so as to release plunger 51 for reciprocation, the latter partakes of controlled reciprocation as before with plunger 51^c moving along with it substantially as earlier described above.

In Figures 15 and 16 I have shown a winding 55 wound or mounted on a suitable insulating form or spool and provided with insulating end plates 57 and 58, as before, and assembled to the plate support 60 by metal end plates 87 and 88 secured by suitable ears and screws 75. End plate 68 is of paramagnetic material, and adjacent one end thereof it is in flatwise flux-conductive engagement with a small block-like permanent magnet 90 whose opposite end face is in similar flux-conductive engagement with a companion paramagnetic plate member 91 shaped substantially the same as plate 88 and being provided with ears or lugs through which pass screws 92 securing it to the plate support 60 and holding it parallel to the companion plate 88.

Permanent magnet block 90 rests against the plate support 60 between upstanding lugs 69^b and 69^c and is further held against dislocation by overlying lugs 91^a and 93^a of the metal plates.

The winding unit 53—55—57 has a central 75 channel or bore therethrough, as before, and the

15

parallel plates 87, 88, and 91 are provided with aligned circular apertures 87^b, 88^b, and 91^b which are aligned with the cylindrical bore of the winding unit, all of them being of a diameter so that the sub-assembly as seen in Figure 16 can be sleeved, or slid onto the internally projecting tubular casing part 36, as shown in Figure 15, screws 67 and 68 securing the sub-assembly to the inclined brackets 63 and 64, adjustably by way of the slots 65 and 66.

The tubular casing part 36 again contains a plunger 51 and striker rod 50, and in the form shown the plunger 51, in its at-rest position, is located with its magnetic center displaced upwardly to the right of the magnetic center of the solenoid winding 55 so that upon energization of the latter, plunger 51 is drawn downwardly to impact striker 50 against the gong 45.

Intermediate of its ends, striker rod 50 carries a paramagnetic plunger 51^a, which may be of chromium-plated soft iron, for coaction with the permanent magnet flux to which it is subjected by the extension poles 88 and 91 which, like the other extension poles above described, surround the tubular part 36; these parts coat to hold the striker 50 in an at-rest position where it is out of contact with the gong 45 and to give the plunger 51 and striker 50 a return or reverse stroke of movement at the conclusion of each power stroke effected by the magnetic force of winding 55 on the part 51.

The plunger 51^a is of a length in relation to the axial dimension of the permanent magnet circuit substantially as indicated in Figure 15, and permanent magnet flux flowing axially in the plunger 51^a tends to force and hold the plunger 51^a with its mid-point substantially coincident with a mid-plane between the pole pieces 88 and 91. When winding 55 is given an energizing pulse, plunger 51 is forced downwardly to the left in Figure 15 to impact the striker 50 against the gong 45 and in the course of that stroke of movement, plunger or core 51^a opens up, increasingly in axial direction, what is in effect an axial flux gap between the upper end of plunger 51^a and the flux guiding surfaces about the hole 88^b in the pole piece 88, thus rapidly diminishing, at a rapidly increasing rate, the pull or holding action of the permanent magnet flux on the plunger 51^a and hence upon the moving parts; this means that the force opposing the magnetic force exerted by winding 55 on part 51 rapidly diminishes so that the rapidly increasing magnetic force of winding 55 on part 51, effected not only by a rise in instantaneous current value in the winding 55 but also by the square law solenoid effect, can cause the striker 50 to impact the gong 45 at high velocity and energy. Upon substantial collapse of the pulse of energizing current in winding 55, with resulting substantial collapse of the magnetic field produced by the winding 55, the flux of permanent magnet 90, flowing from pole piece 88 in general axial direction to the upper end of core 51, across the then relatively long axial flux gap, snaps the core 51^a and the parts connected to it upwardly to the right in Figure 15 to restore it to its at-rest position or to permit repetition of the just-described cycle of operation upon the ensuing pulse of energization of winding 55.

During gong striking stroke and the ensuing stroke of the moving parts, the effectiveness of change in the axial flux gap between core 51^a and pole piece 88^b is maintained by the substantial invariability of the annular radial flux gap

25
30

16

between the concentric surfaces of the hole 91^b in the pole piece 91 and the cylindrical surface of core 51^a, that radial flux gap being of relatively small dimension. However, any desired characteristic of change in magnetic force on the core 51^a in relation to axial displacement of the core 51^a may be achieved by appropriately shaping the coacting flux guiding faces of the parts. For example, a higher rate of change in reluctance of the flux gaps in the magnetic circuit of the permanent magnet 90 may be effected as by appropriately changing the radii of the external surface of the core 51^a, as is indicated in the fragmentary view of Figure 17 where an intermediate portion of core 51^a is tapered, as indicated at 93, so that when the tapered portion, on downward movement of core 51^a, comes more and more into juxtaposition to the flux face 91^b of pole piece 91, that radial flux gap is increased in effective radial dimension and its reluctance correspondingly increased.

In any case, the parts are so proportioned and the winding unit sub-assembly so adjusted lengthwise of the casing tube 36 that gong 45 (see Figure 15) coacts with the permanent magnet circuit in that it prevents the core 51^a from such excessive axial movement as would bring it out of the desired coacting relation with the permanent magnet circuit for effecting a return stroke of movement.

Winding 55 may be energized in any suitable manner as will now be clear, with an appropriate energizing impulse or succession of pulses of current. Illustratively, but not by way of limitation, it may be energized from a direct current source with the aid of a suitable circuit interrupter which may be of any suitable type and may be related in any suitable manner to the magnetic field produced by winding 55, and in Figure 16 an illustrative vibrating form of interrupter is shown and generally indicated by the reference character 95.

The interrupter may comprise a flat leaf spring 96 insulatingly supported in any suitable manner, as indicated at 97, from one end edge of the pole piece plate 88, its extreme end portion 96^a being provided with suitable means for connecting an electric conductor thereto. Leaf spring 96, preferably of steel, has secured to it, as by riveting, a soft iron plate-like armature 98 which terminates in juxtaposition to the vertical end edge face, as seen in Figure 16, of the winding unit end plate 87 which is made of sheet steel or the like. Accordingly parts 88, 96, 98, and 87 form a magnetic circuit for flux produced by the winding 55, so that upon energization of winding 55 armature 98 is attracted and moved toward the part 87, lessening the flux gap therebetween. This movement of armature 98 is utilized to break the circuit of winding 55, and this may be done by a contact element 99 carried at the free and somewhat bent end of flat spring 96 and normally, under the action of spring 96, held in engagement with an adjustable stationary contact which can be in the form of a contact screw 100 carried in a bracket 101 which is insulatingly supported in any suitable manner on the plate support 60 and which is provided with a binding screw 102 for connecting the conductor thereto. By setting screw 100 against the bias of spring 96, the normal at-rest dimension of the flux gap between parts 98 and 87 may be adjusted to give the desired frequency of vibration and hence frequency of circuit interruption and of energizing 75 pulses for the winding 55. In Figure 18 is dia-

grammatically shown the series connection of the winding 55 and interrupter 95 across the connector tabs 61 and 62 carried by the insulating plate 58 of the winding unit.

The various adjustments described can be empirically arrived at in course of assembly or test and before the mechanism becomes sealed within the casing 20—21—36; with the interrupter also enclosed, the device may be safely used in atmospheres where there is risk of explosive content, any sparking at the interrupter contacts being thus rendered harmless. It will be understood that in place of the interrupter 95, the sub-assembly of Figure 16 may have mounted on it a rectifier like the rectifier 71 of Figure 8 where impulse energization of that kind from an alternating current source may be desired, in which case the circuit arrangement is as shown in Figure 9; also, the interrupter arrangement shown in Figure 16 is intended to be illustrative of how an interrupter may be employed in not only the forms of Figures 15 and 17, but also in any other form, for example, that of Figures 8 and 10 where impulse energization in that manner is desired.

In Figure 17 I have shown the embodiment of Figure 15 arranged for ice-breaking action, and there I have arranged the paramagnetic plunger parts 51 and 51^a for relative axial movement, in that striker 50 is mechanically connected to plunger 51^a and plunger 51 is provided with a downwardly extending stem 51^f, preferably of non-magnetic material, being surrounded by a spring 52^e which is interposed between the two plungers and normally holds them apart so that stem 51^f is spaced from the upper end of plunger 51, somewhat as in the arrangement of Figure 10; preferably a short cushioning spring 52^g is interposed between the sleeved inner end of tubular casing 36 and the upper end of plunger 51^a.

The at-rest position of the parts is substantially as shown in Figure 17, being so held by the action of the permanent magnet flux on the plunger 51^a. Should striker 50 be immobilized, as by an accumulation of ice as above noted, the plunger 51^a remains stationary upon subsequent impulse energization of the winding 55 and the flux of the latter, produced internally and coaxially of the tubular part 36 that is within the winding 55, exerts a strong pull in downward direction on the plunger 51 and in effect snaps the latter downwardly at substantial velocity and against the action of spring 52^e, which can be of relatively small strength, to impact the stem 51^f against the plunger 51^a and by the energy of the resultant blow driving the striker 50 into the ice formation; when the energizing impulse ceases or diminishes, the spring 52^e moves the plunger 51 upwardly to position it to be again snapped downwardly upon the succeeding impulse energization of the winding 55 to repeat the cycle.

Such cyclic reciprocity is rapidly repeated as the impulse energization of the winding continues and when the striker 50 is freed, both plungers 51 and 51^a can partake of axial reciprocity somewhat as a unit, though in the course of the downward or power stroke, relative axial movement between them can take place in that, depending upon correlation of strength of spring 52^e to other factors, downward movement of plunger 51 can take place at high enough velocity to impact against the plunger 51^a before the effect of its inertia and the effect of the permanent magnet pull thereon are overcome by the 75

compression of the spring 52^e, in which case the striker 50 is suddenly impelled downwardly at good velocity to effect striking of the gong by the striker 50; when the current impulse energizing the winding 55 ceases or is sufficiently diminished, the permanent magnet flux, aided by some rebound of the striker 50, pulls the parts upwardly to substantially the at-rest position, at which moment the succeeding impulse of energizing current becomes operative upon the plunger system to repeat the cycle where repeated or substantial synchronous striking of the gong is desired. During these actions the spring 52^e desirably serves yieldingly to limit the retrograde stroke of plunger 51 appropriately, and it can also act to prevent the plunger from actually striking closed end of the tubular casing part 36.

The construction in its illustrative embodiments will be seen to have numerous advantages from many viewpoints, such as manufacture, assembly, adjustment or testing, installation, and repair or replacement of parts. For example, a setting of internally adjustable parts once 25 made and the structure assembled and sealed, cannot be detrimentally disturbed by shift or displacement of the gong which cannot be rotatively displaced nor can it be removed and put back in other than its initial position.

Moreover, it will be seen that the invention provides a signalling device in which the various objects above set forth and also elsewhere indicated are successively achieved; the construction will be seen to be rugged and dependable, particularly under widely varying conditions of practical use, and particularly under adverse weather conditions such as are met with on shipboard, for example.

As many possible embodiments may be made of the above invention and as many changes might be made in the embodiments above set forth, it is to be understood that all matter hereinbefore set forth or shown in the accompanying drawings is to be interpreted as illustrative and not in a limiting sense.

I claim:

1. A weatherproof and de-icing signalling construction comprising means forming a sealed casing having an opening in a wall thereof from which a re-entrant tube-like casing part extends upwardly and inwardly into the casing to form an air trap against the rise of water thereinto, a gong supported externally of said casing with a portion thereof adjacent said opening, a striker in said re-entrant casing part and reciprocable through said opening for striking said gong, paramagnetic means within said re-entrant casing part and protected against water by said air trap and reciprocably movable therein in strokes toward and away from said opening, said paramagnetic means comprising a plurality of paramagnetic plungers having means mechanically interrelating them for movement in the same direction on each stroke and for movement of one relative to the other, one of said paramagnetic plungers having mechanical connection with said striker whereby the latter is reciprocated into striking engagement with said gong upon movement of said plungers in said strokes and whereby, when said striker is immobilized by icing at its outer end and thereby the plunger connected to it is also immobilized, the other of said plungers may partake of movement toward and away therefrom, and magnetic flux-producing means controlling actuation of said

paramagnetic plungers and including electro-magnetic winding means within said sealed casing and coacting upon energization to reciprocate both plungers to effect striking of said gong by said striker and, upon immobilization of said one plunger by icing of the striker, to reciprocate the other plunger relative thereto to dissipate its kinetic energy thereon through said striker to free itself from the icing.

2. A weatherproof and de-icing signalling construction as claimed in claim 1 in which said magnetic flux-producing means includes also permanent magnet means the flux of which acts upon said plunger that is mechanically connected to the striker to hold it and the striker, during de-energization of said winding means, in retracted position and in which the flux produced by said winding means, when energized, acts upon the other plunger.

3. A weatherproof and de-icing signalling construction as claimed in claim 1 in which said magnetic flux-producing means includes also permanent magnet means the flux of which acts upon said plunger that is mechanically connected to the striker to hold it and the striker, during de-energization of said winding means, in retracted position and in which the other plunger surrounds and is slideable relative to the striker for reciprocation therealong toward and away from said striker-connected plunger and the flux produced by said winding means, when energized, acting upon the latter to effect striking reciprocation of the striker and, upon immobilization thereof, acts through said striker-connected plunger upon the other to reciprocate the latter relative to the former along said striker.

4. A weatherproof and de-icing signalling construction as claimed in claim 1 in which said magnetic flux-producing means includes also permanent magnet means the flux of which acts upon said plunger that is mechanically connected to the striker to hold it and the striker, during de-energization of said winding means, in retracted position and in which the other plunger is interposed between said striker-connected plunger and the inner end of said re-entrant casing part for reciprocating movement toward and away from said striker-connected plunger, the flux of said winding means, when energized, acting upon the latter for striking reciprocation of said striker and, upon immobilization thereof, acting upon said other plunger to reciprocate it into impacting engagement with said striker-connected plunger.

5. In a signalling construction, in combination, means forming a sealed casing having a substantially vertical wall externally of which is mounted a gong, said wall having an opening adjacent a part of the gong to be struck and a re-entrant tube-like casing part extending from said opening inwardly and upwardly into the interior of the sealed casing and forming an air trap to prevent rise of water thereinto, a paramagnetic plunger slideable in said tube-like casing part and protected against water by said air trap, said plunger having striker means operating upon said gong portion through said opening, means for holding said striker means in an at-rest position out of contact with said gong to prevent water accumulation and freezing thereat and for actuating said plunger to cause striking of said gong comprising permanent magnet means producing a magnetic field the flux of which exerts a magnetic force on said plunger to hold it and said striker means against descent

in said tube-like casing part, and electro-magnetic winding means within said sealed casing and extending about said tube-like casing part to produce a magnetic field, when energized, the flux of which acts upon said plunger through the walls of said tube-like casing part.

6. In a signalling construction, in combination, means forming a sealed casing having a substantially vertical wall externally of which is mounted a gong, said wall having an opening adjacent a part of the gong to be struck and a re-entrant tube-like casing part extending from said opening inwardly and upwardly into the interior of the sealed casing and forming an air trap to prevent rise of water thereinto, a paramagnetic plunger slideable in said tube-like casing part and protected against water by said air trap, said plunger having striker means operating upon said gong portion through said opening, means for holding said striker means in an at-rest position out of contact with said gong to prevent water accumulation and freezing thereat and for actuating said plunger to cause striking of said gong comprising spring means in said tube-like casing part and interposed between the inner end thereof and said plunger for impelling the plunger and striker means downwardly to strike said gong, permanent magnet means exerting upward force on said plunger and partially compress said spring means to hold said plunger in a position with the striker means out of contact with said gong, and an electro-magnetic winding about said re-entrant tube-like casing part and producing, when energized by current pulses of one sign, a magnetic field for each pulse in a direction additive to that of said permanent magnet means and thereby further compress said spring means during each of said energizing pulses.

7. In a signalling construction, in combination, means forming a sealed casing having a substantially vertical wall externally of which is mounted a gong, said wall having an opening adjacent a part of the gong to be struck and a re-entrant tube-like casing part extending from said opening inwardly and upwardly into the interior of the sealed casing and forming an air trap to prevent rise of water thereinto, a paramagnetic plunger slideable in said tube-like casing part and protected against water by said air trap, said plunger having striker means operating upon said gong portion through said opening, means for holding said striker means in an at-rest position out of contact with said gong to prevent water accumulation and freezing thereat and for actuating said plunger to cause striking of said gong comprising permanent magnet means within said sealed casing and having spaced pole extensions related to the walls of said re-entrant tube-like casing part to direct unidirectional magnetic flux therethrough for action upon said plunger to hold it and said striker means against descent into engagement with said gong, and means comprising an electro-magnetic winding within said sealed casing to produce a magnetic field, when energized, coacting to project said plunger and striker means downwardly.

8. In a signalling construction, in combination, means forming a sealed casing having a substantially vertical wall externally of which is mounted a gong, said wall having an opening adjacent a part of the gong to be struck and a re-entrant tube-like casing part extending from said opening inwardly and upwardly into the interior of the sealed casing and forming an air trap to

prevent rise of water thereinto, a paramagnetic plunger slideable in said tube-like casing part and protected against water by said air trap, said plunger having striker means operating upon said gong portion through said opening, means for holding said striker means in an at-rest position out of contact with said gong to prevent water accumulation and freezing thereat and for actuating said plunger to cause striking of said gong comprising permanent magnet means within said sealed casing and having pole extensions axially spaced relative to the axis of said re-entrant tube-like casing part to produce unidirectional magnetic flux within said re-entrant casing part, said plunger having two parts, one of which is acted upon by said flux to hold it and said striker means against descent into engagement with said gong, and an electro-magnetic winding within said sealed casing and producing, when energized, a magnetic field acting through the walls of said re-entrant tube-like casing part and upon the other part of said plunger.

9. In a signalling construction, in combination, means forming a sealed casing having a substantially vertical wall externally of which is mounted a gong, said wall having an opening adjacent a part of the gong to be struck and a re-entrant tube-like casing part extending from said opening inwardly and upwardly into the interior of the sealed casing and forming an air trap to prevent rise of water thereinto, a paramagnetic plunger slideable in said tube-like casing part and protected against water by said air trap, said plunger having striker means operating upon said gong portion through said opening, means for holding said striker means in an at-rest position out of contact with said gong to prevent water accumulation and freezing thereat and for actuating said plunger to cause striking of said gong comprising permanent magnet means within said sealed casing and having two pole extensions spaced along the axis of said re-entrant tube-like casing part to produce through the walls and within the latter unidirectional magnetic flux along the axial flux gap between said spaced pole extensions and into which axial flux gap the upper portion of said plunger extends, said gong acting through said striker means to prevent descent of said plunger completely out of said axial flux gap whereby the pull of said flux on said plunger returns and holds said striker means out of engagement with said gong, and electro-magnetic winding means within said sealed casing and coacting to project said plunger and striker downwardly.

10. In a signalling construction, in combination, means forming a sealed casing having a substantially vertical wall externally of which is mounted a gong, said wall having an opening adjacent a part of the gong to be struck and a re-entrant tube-like casing part extending from said opening inwardly and upwardly into the interior of the sealed casing and forming an air trap to prevent rise of water thereinto, a paramagnetic plunger slideable in said tube-like casing part and protected against water by said air trap, said plunger having striker means operating upon said gong portion through said opening, means for holding said striker means in an at-rest position out of contact with said gong to prevent water accumulation and freezing thereat and for actuating said plunger to cause striking of said gong comprising permanent magnet means within said sealed casing and having a plurality of axially spaced pole extensions along said re-entrant tube-

like casing part between two of which is formed one axial flux gap and two of which form a second axial flux gap, for flux from said permanent magnet means, said two axial flux gaps being substantially axially aligned for flux conduction within said tube-like casing part for coaction with said plunger whereby the magnetic forces exerted axially on said plunger tend to force it to substantially bridge one or the other of said axial flux gaps, and electro-magnetic winding means in said sealed casing and coaxial with said re-entrant tube-like casing part for affecting the relative effects of the permanent magnet fluxes in said two flux gaps and thereby effect movement of said plunger and striker means.

11. In a signalling construction, in combination, means forming a sealed casing having a substantially vertical wall externally of which is mounted a gong, said wall having an opening adjacent a part of the gong to be struck and a re-entrant tube-like casing part extending from said opening inwardly and upwardly into the interior of the sealed casing and forming an air trap to prevent rise of water thereinto, a paramagnetic plunger slideable in said tube-like casing part and protected against water in said air trap, said plunger having striker means operating upon said gong portion through said opening, means for holding said striker means in an at-rest position out of contact with said gong to prevent water accumulation and freezing thereat and for actuating said plunger to cause striking of said gong comprising permanent magnet means within said sealed casing and having three pole extensions axially spaced along said re-entrant tube-like casing part and thereby providing two axially aligned flux gaps within said tube-like casing part for coaction with said plunger, whereby said plunger tends to assume a position in which it substantially bridges one of said axial flux gaps or the other, and electro-magnetic winding means within said sealed casing effective, when energized, to alternately change the effective flux values in said two axial flux gaps and thereby effect reciprocation of said plunger and striker means.

12. In a signalling construction, in combination, means forming a sealed casing having a substantially vertical wall externally of which is mounted a gong, said wall having an opening adjacent a part of the gong to be struck and a re-entrant tube-like casing part extending from said opening inwardly and upwardly into the interior of the sealed casing and forming an air trap to prevent rise of water thereinto, a paramagnetic plunger slideable in said tube-like casing part and protected against water in said air trap, said plunger having striker means operating upon said gong portion through said opening, means for holding said striker means in an at-rest position out of contact with said gong to prevent water accumulation and freezing thereat and for actuating said plunger to cause striking of said gong comprising permanent magnet means within said sealed casing and having three pole extensions axially spaced along said re-entrant tube-like casing part and thereby providing two axially aligned flux gaps within said tube-like casing part for coaction with said plunger, whereby said plunger tends to assume a position in which it substantially bridges one of said axial flux gaps or substantially bridges one of said axial flux gaps or the other, stop means to prevent downward movement of said plunger beyond that point at which the lower of said two axial flux gaps is

effective to hold the plunger against the upward pull of the flux in the upper flux gap, and electro-magnetic winding means within said sealed casing which, when energized, overcomes the holding force of the upper flux gap on said plunger and thereby controls descent thereof to strike said gong with said striker means.

13. In a signalling construction, in combination, means forming a sealed casing having a substantially vertical wall externally of which is mounted a gong, said wall having an opening adjacent a part of the gong to be struck and a re-entrant tube-like casing part extending from said opening inwardly and upwardly into the interior of the sealed casing and forming an air trap to prevent rise of water thereinto, a paramagnetic plunger slideable in said tube-like casing part and protected against water in said air trap, said plunger having striker means operating upon said gong portion through said opening, means for holding said striker means in an at-rest position out of contact with said gong to prevent water accumulation and freezing thereat and for actuating said plunger to cause striking of said gong comprising permanent magnet means within said sealed casing and having three pole extensions axially spaced along said re-entrant tube-like casing part and thereby providing two axially aligned flux gaps within said tube-like casing part for coaction with said plunger, whereby said plunger tends to assume a position in which it substantially bridges one of said axial flux gaps or the other, stop means to prevent downward movement of said plunger beyond that point at which the lower of said two axial flux gaps is effective to hold the plunger against the upward pull of the flux in the upper flux gap, and electro-magnetic winding means within said sealed casing and coacting, when energized, to oppose the permanent magnet flux in said upper flux gap and to aid the permanent magnet flux in the lower of said axial flux gaps and thereby effect descent of said plunger and striking of said gong with said striker means.

14. In a signalling construction, in combination, means forming a sealed casing having a substantially vertical wall externally of which is mounted a gong, said wall having an opening adjacent a part of the gong to be struck and a re-entrant tube-like casing part extending from said opening inwardly and upwardly into the interior of the sealed casing and forming an air trap to prevent rise of water thereinto, a paramagnetic plunger slideable in said tube-like casing part and protected against water by said air trap, said plunger having striker means operating upon said gong portion through said opening, means for holding said striker means in an at-rest position out of contact with said gong to prevent water accumulation and freezing thereat and for actuating said plunger to cause striking of said gong comprising permanent magnet means within said sealed casing and having pole extensions axially spaced relative to the axis of said re-entrant tube-like casing part, one of which pole extensions comprising an axially extending part to produce between the latter and another of said pole extensions a unidirectional magnetic flux within said re-entrant casing part that acts upon said plunger to hold it and said striker means against descent into engagement with said gong, and an electro-magnetic winding coaxial with said re-entrant tube-like casing part and said pole extension part and by its magneto-motive force alter the holding force of the permanent

magnet flux on said plunger and cause movement of the latter and said striker means.

15. In a signalling construction, in combination, means forming a sealed casing having a substantially vertical wall externally of which is mounted a gong, said wall having an opening adjacent a part of the gong to be struck and a re-entrant tube-like casing part extending from said opening inwardly and upwardly into the interior of the sealed casing and forming an air trap to prevent rise of water thereinto, a paramagnetic plunger slideable in said tube-like casing part and protected against water by said air trap, said plunger having striker means operating upon said gong portion through said opening, means for holding said striker means in an at-rest position out of contact with said gong to prevent water accumulation and freezing thereat and for actuating said plunger to cause striking of said gong comprising permanent magnet means within said sealed casing and having pole extensions axially spaced relative to the axis of said re-entrant tube-like casing part to produce unidirectional magnetic flux within said re-entrant casing part, said plunger having two parts, one of which is acted upon by said flux to hold it and said striker means against descent into engagement with said gong, said part being of varying cross-section to increase the reluctance in the path of flow of said flux upon downward movement of the plunger, and an electro-magnetic winding within said sealed casing and producing, when energized, a magnetic field acting through the walls of said re-entrant tube-like casing part and upon the other part of said plunger.

16. In a signalling construction, in combination, means forming a sealed casing and comprising at least two separable casing parts and provided with means forming a sealed connection therebetween, a wall member, said sealed casing means having an aperture with a re-entrant tube-like casing part extending from said aperture inwardly and upwardly into the interior of the sealed casing and forming an air trap to prevent rise of water thereinto, a signalling device supported externally of said casing and in operative relation to said aperture, and means for activating said signalling device comprising a movable paramagnetic member in said re-entrant tube-like casing part and protected against water by said air trap and having means responsive to its movement and operable through said aperture for activating said signalling device and means for controlling actuation of said movable paramagnetic member and comprising electro-magnetic means within said sealed casing for coacting through the walls of said re-entrant tube-like casing part to effect movement of said paramagnetic member.

17. In a signalling construction, in combination, means forming a sealed casing that has an inwardly and upwardly extending casing part that is re-entrant from an opening in a wall of the casing and thereby forming an air trap to prevent rise of water thereinto, a signalling device external of said casing and operatively related to said opening, and means for activating said signalling device comprising a movable paramagnetic member in said re-entrant casing part and plunger actuating means including electro-magnetic means within said sealed casing for coacting magnetically through the walls of said re-entrant casing part with said paramagnetic member.

18. In a signalling construction, in combination, means forming a sealed casing having a substantially vertical wall externally of which is mounted a gong, said wall having an opening adjacent a part of the gong to be struck and a re-entrant tube-like casing part extending from said opening inwardly and upwardly into the interior of the sealed casing and forming an air trap to prevent rise of water thereinto, a paramagnetic plunger slidable in said tube-like casing part and protected against water by said air trap, said plunger having striker means operating upon said gong portion through said opening, and means for actuating said plunger comprising electromagnetic means within said sealed casing for producing a magnetic flux that operates upon said plunger through the wall of said re-entrant tube-like casing part.

19. In a signalling construction as claimed in claim 18 in which said gong has a dished portion that overlies and covers over said opening and in which said re-entrant tube-like casing part extends at an angle to the central vertical axis of the gong with its axis intersecting the gong at a point displaced from said vertical gong axis whereby the gong portion struck by said striker means is of an angularity or curvature to prevent accumulation of water thereat.

20. In a signalling construction, in combination, means forming a sealed casing and comprising at least two separable casing parts provided with means forming a sealed connection therebetween, one of which parts has an inwardly and upwardly extending casing part that is re-entrant from an opening therein and thereby forming an air trap to prevent rise of water into said re-entrant casing part, a signalling device external of said casing and operatively related to said opening, means for activating said signalling device comprising paramagnetic means in said re-entrant casing part and protected against water by said air trap with means within said sealed casing for producing a magnetic flux for coaction through the walls of said re-entrant casing part with said paramagnetic means, and means for securing said two separable casing parts together and including means preventing assembly to the other part of that casing part which has the re-entrant casing part with the latter in inverted position.

21. In a signalling construction, in combination, means forming a sealed casing having mounted externally thereof a gong with its axis substantially horizontal and with the concave side thereof toward the casing means, said casing means comprising at least two separable casing parts provided with means forming a sealed connection therebetween, one of said parts having an opening with which the open end of a tube member, which extends into the interior of said casing and is closed off at its inner end, is in sealed connection, the line of the axis of said tube member as extended through said open end intersecting said concave side of said gong at a point below the horizontal diameter of the gong and displaced from the vertical diameter thereof, movable paramagnetic means in said tube member for activating said gong through the outer open end thereof and operating thereon at substantially said point on the concave side of said gong, and means within said sealed casing for producing magnetic flux which acts upon said paramagnetic means through the walls of said tube member.

22. In a signalling construction, in combination,

means forming a sealed casing and comprising at least two separable casing parts provided with means forming a sealed connection therebetween, one of said parts having an opening with which the open end of a tube member, which extends into the interior of said casing and is closed off at its inner end, is in sealed connection, a signalling device external of said casing and operatively related to said opening, movable paramagnetic means in said tube member for activating said signalling device through the outer open end thereof, and means within said sealed casing for producing magnetic flux which acts upon said paramagnetic means through the walls of said tube member, said tube member extending into said sealed casing in upward direction and forming an air trap to prevent rise of water thereinto, and slidably supporting and guiding said paramagnetic means, and means responsive to slideable actuation of said paramagnetic means and coacting with said signalling device through the outer open end of said tube member.

23. In a signalling construction, in combination, means forming a sealed casing and comprising at least two separable casing parts provided with means forming a sealed connection therebetween, one of said parts having an opening with which the open end of a tube member, which extends into the interior of said casing and is closed off at its inner end, is in sealed connection, a signalling device external of said casing and operatively related to said opening, movable paramagnetic means in said tube member for activating said signalling device through the outer open end thereof, and means within said sealed casing for producing magnetic flux which acts upon said paramagnetic means through the walls of said tube member, said opening being in a substantially vertical wall portion of the casing part and said tube member extending upwardly into the sealed casing at an acute angle to said substantially vertical wall.

24. In a signalling construction as claimed in claim 23 in which the open end portion of said tube member projects downwardly at an acute angle through and beyond said opening to the exterior of the casing wall and forms a water shed.

25. In a signalling construction as claimed in claim 23 in which said flux-producing means comprises electromagnetic winding means having an axial bore therein dimensioned to slide over said tube member and being thereby sleeved onto the latter from the inner end thereof for producing a magnetic field acting upon said plunger means through the walls of said tube member, said winding means having a frame-like support means therefor that falls in a plane parallel to the axis of said bore and said casing having internal support means that extends at said acute angle to said vertical wall to slidably receive thereon said frame-like support.

26. In a signalling construction, in combination, means forming a casing having an opening in a wall thereof with one end of a tube member rigidly secured thereto at said opening and extending inwardly of said casing like a cantilever, a gong supported externally of said casing with a portion thereof adjacent said opening, paramagnetic plunger means in said tube member and having striker means operable upon said gong through the outer end of said tube member, a control unit comprising spaced pole piece members, electro-magnetic winding means and permanent magnet means coacting therewith to pro-

duce magnetic fluxes, with means securing them together as a unit, said winding means having an axial bore therein whereby said control unit is sleeved onto said tube member and said magnetic fluxes brought into coaction with said plunger means through the walls of said tube member, and means for securing said control unit against shift lengthwise of said tube member, the flux from said permanent magnet means coacting, when said winding is de-energized, to hold said plunger means in an at-rest position.

27. In a signalling construction, in combination, means forming a casing having an opening in a wall thereof with one end of a cantilever tube member rigidly secured thereto at said opening and extending inwardly of said casing, a gong presenting a peripheral portion thereof adjacent said opening, said casing and said gong having interfitting means for non-rotatively securing said gong at its center to said casing to prevent presentation of any other peripheral portion thereof to said opening, paramagnetic plunger means in said tube member and having striker means operable upon said peripheral portion of said gong through the outer end of said tube member, a control unit sleeved onto said cantilever tube member from the inner end thereof and comprising electro-magnetic winding means for producing a magnetic field acting upon said plunger means through the walls of said tube member whereby the coaction between said magnetic field, said plunger means, said striker means, and said gong portion may be determined by shifting said control unit along said tube member, said casing having therein a guideway-forming support extending parallel to and spaced from said tube member for slidably receiving said control unit, and means for securing said unit in adjusted position along said support, said interfitting means, in preventing rotary displacement of said gong portion, preventing impairment of the setting of the aforesaid coaction.

28. In a signalling construction as claimed in claim 27 in which said control unit comprises permanent magnet means producing a magnetic field acting upon said paramagnetic means, during de-energization of said winding means, to hold it and said striker in retracted position relative to said gong and tube member.

29. In a signalling construction, in combination, a supporting frame carrying a signalling element, movable paramagnetic means for actuating said signalling element, said supporting frame having means movably supporting said paramagnetic means for coaction with said signalling element, a control unit for holding said paramagnetic means in an at-rest position and for actuating it comprising permanent magnet means producing a magnetic field the flux of which exerts magnetic force on said paramagnetic means to hold it in at-rest position and electromagnetic winding means for producing, when energized, a magnetic field coacting to effect movement of said paramagnetic means, said supporting frame having support means by which said control unit is movably supported relative to said paramagnetic means whereby the position of said permanent magnet means and said winding means relative to said movable paramagnetic means may be determined, and means for securing said control unit in position.

30. In a signalling construction, in combination, a supporting frame carrying a signalling element, movable paramagnetic means for actuating said signalling element, said supporting frame

having means movably supporting said paramagnetic means for coaction with said signalling element, a control unit for holding said paramagnetic means in an at-rest position and for actuating it comprising permanent magnet means producing a magnetic field the flux of which exerts magnetic force on said paramagnetic means to hold it in at-rest position and electromagnetic winding means for producing, when energized, a magnetic field coacting to effect movement of said paramagnetic means, said permanent magnet means and said winding means having means interrelating both to a common flux gap across which the flux of both magnetic means is effective whereby the flux of said winding means, when energized, by alternating current, is alternately additive to and subtractive from the flux of said permanent magnet means, said supporting frame having support means by which said control unit is movably supported relative to said paramagnetic means whereby the position of said permanent magnet means and said winding means relative to said movable paramagnetic means may be determined, and means for securing said control unit in position.

31. In a signalling construction, in combination, a supporting frame carrying a signalling element, movable paramagnetic means for actuating said signalling element, said supporting frame having means movably supporting said paramagnetic means for coaction with said signalling element, a control unit for holding said paramagnetic means in an at-rest position and for actuating it comprising permanent magnet means producing a magnetic field the flux of which exerts magnetic force on said paramagnetic means to hold it in at-rest position and electromagnetic winding means for producing, when energized, a magnetic field coacting to effect movement of said paramagnetic means, said control unit carrying a rectifier in circuit with said winding means whereby the latter produces its magnetic field only on alternating half-waves of energizing alternating current, said supporting frame having support means by which said control unit is movably supported relative to said paramagnetic means whereby the position of said permanent magnet means and said winding means relative to said movable paramagnetic means may be determined, and means for securing said control unit in position.

32. In a signalling construction, in combination, a supporting frame carrying a signalling element, movable paramagnetic means for actuating said signalling element, said supporting frame having means movably supporting said paramagnetic means for coaction with said signalling element, a control unit for holding said paramagnetic means in an at-rest position and for actuating it comprising permanent magnet means producing a magnetic field the flux of which exerts magnetic force on said paramagnetic means to hold it in at-rest position and electromagnetic winding means for producing, when energized, a magnetic field coacting to effect movement of said paramagnetic means, said permanent magnet means of said control unit having spaced extension poles forming a flux gap to which said paramagnetic means is subjected for being held in at-rest position, said flux gap being substantially independent of the flux of the magnetic field of said winding means, said supporting frame having support means by which said control unit is movably supported relative to said paramagnetic means whereby

the position of said permanent magnet means and said winding means relative to said movable paramagnetic means may be determined, and means for securing said control unit in position.

33. In a signalling construction, in combination, a supporting frame carrying a signalling element, movable paramagnetic means for actuating said signalling element, said supporting frame having means movably supporting said paramagnetic means for coaction with said signalling element, a control unit for holding said paramagnetic means in an at-rest position and for actuating it comprising permanent magnet means producing a magnetic field the flux of which exerts magnetic force on said paramagnetic means to hold it in at-rest position and electromagnetic winding means for producing, when energized, a magnetic field coacting to effect movement of said paramagnetic means, said control unit carrying a current interrupter in circuit with said winding means and coacting with magnetic flux produced thereby for energizing said winding means in successive pulses of energizing current, said supporting frame having support means by which said control unit is movably supported relative to said paramagnetic means whereby the position of said permanent magnet means and said winding means relative to said movable paramagnetic means may be determined, and means for securing said control unit in position.

34. In a signalling construction, in combination, a supporting frame carrying a signalling element, movable paramagnetic means for actuating said signalling element, said supporting frame having means movably supporting said paramagnetic means for coaction with said signalling element, a control unit for holding said paramagnetic means in an at-rest position and for actuating it comprising permanent magnet means producing a magnetic field the flux of which exerts magnetic force on said paramagnetic means to hold it in at-rest position and electromagnetic winding means for producing, when energized, a magnetic field coacting to effect movement of said paramagnetic means, said permanent magnet means of said control unit having a plurality of extension poles between which are formed two spaced flux gaps for permanent magnet flux and into either of which said paramagnetic means is movable, said winding means coacting with at least one of said flux gaps to affect the permanent magnet flux therein, said supporting frame having support means by which said control unit is movably supported relative to said paramagnetic means whereby the position of said permanent magnet means and said winding means relative to said movable paramagnetic means may be determined, and means for securing said control unit in position.

35. In a signalling construction, in combination, a supporting frame carrying a signalling element, movable paramagnetic means for actuating said signalling element, said supporting frame having means movably supporting said paramagnetic means for coaction with said signalling element, a control unit for holding said paramagnetic means in an at-rest position and for actuating it comprising permanent magnet means producing a magnetic field the flux of which exerts magnetic force on said paramagnetic means to hold it in at-rest position and electromagnetic winding means for producing, when energized, a magnetic field coacting to effect movement of said paramagnetic means, said permanent magnet

means on said control unit having a plurality of spaced poles to provide two flux gaps for the permanent magnet flux that coacts with said paramagnetic means and said winding means being related thereto to alternately change, upon energization by alternating current, the effective flux values of said two flux gaps and thereby effect actuation of said movable paramagnetic means, said supporting frame having support means by which said control unit is movably supported relative to said paramagnetic means whereby the position of said permanent magnet means and said winding means relative to said movable paramagnetic means may be determined, and means for securing said control unit in position.

36. In a signalling construction, in combination, a signalling element and a reciprocable striker and paramagnetic plunger means therefor having means guiding them for reciprocation in reversible strokes, said paramagnetic plunger means comprising two paramagnetic plungers having means mechanically interrelating them for movement in the same direction on each stroke and for movement of one relative to the other, and magnetic flux-producing means controlling said paramagnetic means and comprising permanent magnet means acting thereon to hold it and said striker in an at-rest position and electro-magnetic winding means coacting upon energization to reciprocate both plungers for striking actuation of said striker and, upon one of said plungers becoming immovable, to reciprocate the other plunger relative thereto.

37. A signalling construction as claimed in claim 36 in which said permanent magnet means is provided with extension poles spaced along the line of movement of said paramagnetic means to provide an axial flux gap for one of said plungers to coact with for being held in said at-rest position, said electromagnetic winding means and said other plunger being magnetically interrelated so that the flux of said winding acts upon said other plunger substantially independently of said axial flux gap.

38. A signalling construction as claimed in claim 36 in which said permanent magnet means is provided with extension poles spaced along the line of movement of said paramagnetic means to provide an axial flux gap for one of said plungers to coact with for being held in said at-rest position, said electromagnetic winding means being magnetically interrelated to said extension poles so that flux produced by it when energized coacts with permanent magnet flux in said axial flux gap to effect reciprocating actuation of both plungers and to effect reciprocation of only one of them when the other becomes immovable.

39. A signalling construction as claimed in claim 36 in which said permanent magnet means is provided with a plurality of spaced extension poles spaced along the line of movement of said paramagnetic plunger means to provide several axial flux gaps for permanent magnet flux which coact to hold said paramagnetic means in at-rest position and in which said electromagnetic winding means coacts, when energized, to cause effective flux values in said two axial flux gaps to be alternately preponderant over each other and thereby effect reciprocation of said paramagnetic plunger means and upon one of said plungers becoming immovable and thus becoming a stationary part of the magnetic circuit, to effect

31

reciprocation of the other plunger relative thereto.

40. In a signalling construction, in combination, means forming a sealed casing that has an inwardly and upwardly extending tube-like casing part that is re-entrant from an opening in a wall of the casing and thereby forming an air trap to prevent rise of water thereinto, a signalling device external of said casing and operatively related to said opening, reciprocable paramagnetic plunger means in said tube-like re-entrant casing part and having a part which, upon reciprocation of said plunger means, coacts through said opening with said signalling device, said signalling device being positioned in the path of reciprocating movement of said plunger part whereby the signalling device may act to block removal of said plunger means and plunger part from said re-entrant casing part, and plunger-actuating means including electro-magnetic means within said sealed casing for coacting, when energized, magnetically through the walls of said re-entrant casing

32

part with said plunger means for reciprocating the latter and permanent magnet means within said sealed casing for coacting magnetically through the walls of said re-entrant casing part with said paramagnetic plunger means and providing a magnetic field operating upon the latter, during deenergization of said electromagnetic means, to hold said plunger means in inwardly retracted position relative to said re-entrant casing part and thereby hold said plunger part away from said signalling device.
